APPARATUS FOR FORMING BUILDING
BLOCK INSULATING MEMBERS

John T. Gondek, Minneapolis, Minn.

Application October 15, 1949, Serial No. 121,562

26 Claims. (Cl. 1—1)

1

My invention relates to an improvement in apparatus for forming building block insulating members and deals particularly with a device for inserting wire rods through an insulating panel and crimping the rods.

The formation of building blocks having an insulating panel sandwiched between opposite walls thereof has been described in a previous application to H. R. Tregilgas, Serial No. 705,454, filed October 24, 1946. Certain of these blocks are formed with a center insulating panel having a series of spaced wire rods extending therethrough. The ends of these wire rods are bent in such a way as to anchor the rod ends in the material forming the block. The wire rods thus act to connect the portions of the block on opposite sides of the insulating panel and to reinforce the block. The present invention deals with a device for inserting rods through the insulating panel and bending the ends of the rods so that they may be firmly anchored in the block.

A feature of the present invention lies in the provision of a means for supporting a supply of insulating panels and a supply of wire to be inserted therethrough. Means are provided for moving the insulating panels and for inserting wire through the panels at spaced points as the same are advanced.

The panels are moved in a series of steps and wire rods are inserted through the panel between successive steps of the movement. As a result a series of wire rods are inserted through each panel in spaced relation.

A feature of the present invention lies in the provision of a means for crimping the wire on opposite sides of the panel after it has been inserted through the panel. Thus the wire may be inserted through the panel in straight form and the off-set ends of the wire may be produced after the wires have been inserted.

A further feature of the present invention lies in the provision of an apparatus which is operated by hydraulic mechanism throughout. As a result fluid under pressure may actuate all parts of the apparatus in a simple manner and at a relatively low cost.

Another feature of the present invention lies in the provision of an apparatus which is completely automatic in operation. My device acts to remove panels individually from a stack of panels and to advance them in single file past the wire piercing apparatus and the wire crimping apparatus. The wires are inserted automatically in spaced relation and the device continues to function as long as the finished panels are taken from the machine.

2

These and other objects and novel features of my invention will be more clearly and fully set forth in the following specification and claims.

In the drawings forming a part of the specification:

Figure 1 is a side elevational view of the apparatus in operation showing the construction thereof.

Figure 2 is an enlarged elevation view of a detailed portion of the apparatus.

Figure 3 is an end elevation view of the wire inserting portion of the device.

Figure 4 is a side elevation view of the device shown in Figure 3.

Figure 5 is a sectional view through a portion of the wire inserting device illustrated in Figures 3 and 4.

Figure 6 is a transverse sectional view through the wire inserting device showing the construction thereof.

Figure 7 is a bottom plan view of the wire inserting device showing the apparatus in one extreme position.

Figure 8 is a view similar to Figure 7 showing the apparatus in its other extreme position.

Figure 9 is a view similar to Figure 3 showing the apparatus in its other extreme position.

Figure 10 is a sectional view through the wire inserting and cutting elements.

Figure 11 is a bottom plan view of the wire die illustrated in Figure 10.

Figure 12 is a perspective view of the formed structure showing the insulation board in completed form.

Figure 13 is a cross sectional view through the wire clamping device showing the construction thereof.

Figure 14 is a side elevation view of the wire clamping device.

Figure 15 is an elevation view of one of the clamping dies removed from the clamping apparatus.

Figure 16 is an end elevation view of the die shown in Figure 15.

Figure 17 is a top plan view of the die shown in Figure 15.

Figure 18 is an elevation view of the complementary clamping die removed from the clamping apparatus.

Figure 19 is a plan view of the clamping die illustrated in Figure 18.

Figure 20 is a diagrammatic view showing the hydraulic system used in operation of the apparatus.

Figure 21 is a sectional view through one of the controls shown in the system of Figure 20.

Figure 22 is an elevation view of one of the controls shown in Figure 20.

Figure 23 is an outside view showing the opposite end of the control shown in Figure 22.

Figure 24 is a diagrammatic sectional view through the control illustrated in Figures 22 and 23, an indication of the section line being given by the line 24—24 of Figure 22.

The apparatus A is best illustrated in general in Figure 1 of the drawings. As indicated in this figure the apparatus includes a base 10 designed to rest upon a floor or other support and upon which the remainder of the apparatus is mounted. A pair of spaced angular tracks 11 are supported on a horizontal plane above the base 10. Leg units such as 12 and 13 are mounted upon the base 10 by any suitable means and the tracks 11 are connected to the leg units by bolts or cap screws 14 or other suitable means.

A hopper 15 acts to support a supply of insulating panels B. The hopper 15 includes a pair of spaced end walls 16 and 17 which are held in spaced relationship by spacing bolts 19 or other suitable means. A side panel 20 preferably connects the end panels 16 and 17 along one side edge thereof so as to form a guide for the panels B. One side of the hopper may be left open as indicated in Figure 1 of the drawings so that the panels B are visible from one side of the apparatus and may be inserted into the hopper through this open side.

A pivoted lever 21 having a hook shaped lower end 22 is pivotally connected at 23 to an end wall 17 of the hopper 15. The hook end 22 is designed to extend beneath one end of the lowermost panel B in the hopper so as to support this lowermost panel in elevated position. The lever 21 is provided with a lateral extension 24 by means of which the lever may be pivoted. A hydraulic apparatus 25 which will be later described in detail is mounted upon the end wall 17 and may be actuated to pivot the lever 21. When pivoted in a counter-clockwise direction the hook end 22 moves from beneath the lowermost panel in the hopper and allows this lowermost panel to drop onto the tracks 11. When the lever 21 pivots in a clockwise direction upon return movement of the hydraulic apparatus 25, the extremity of the hook shaped end 22 pushes the lowermost panel B slightly to the left as viewed in Figure 1 so that the hook shaped end 22 may support the next adjacent panel B.

A panel feeding element 26 is provided beneath the tracks 11 for engaging the panels and advancing them to the left as viewed in Figure 1. This feeding mechanism includes a platform 27 supported at opposite ends by leaf springs 29 and 30. The leaf springs are connected at their upper ends by bolts or suitable means 31 to the ends of the platform 27. Brackets 32 connect the lower ends of the springs 29 and 30 to the base 10. The leaf springs are arranged in generally parallel relationship so that the platform 27 may advance in a generally horizontal direction.

A hydraulic cylinder 33 is pivotally supported at 34 to a bracket 35 or yoke depending downwardly from the platform 27. The cylinder 33 contains a piston 36 connected to one end of a piston rod 37. The piston rod 37 is pivotally connected at 39 to a suitable yoke 40 on the leg unit 13. Fluid may enter one end of the cylinder 33 so as to move the cylinder relative to the piston 36. Thus by proper intermittent application of fluid into the cylinder 33 the plat-

form 27 may be reciprocated beneath the hopper 15.

As best illustrated in Figures 1 and 2 of the drawings a series of spaced lugs 41, 42, 43, and 44 are mounted upon the platform 27 in longitudinally spaced relationship. Dogs or pawls are pivotally supported on each of these lugs. A pawl 45 is pivotally supported at 46 on the lug 41. This pawl is urged in one extreme position by a spring 47. A second pawl 49 is pivotally connected at 50 to the lug 42. This pawl 49 is urged in a counter-clockwise direction by a spring 51. A third pawl 52 is pivotally connected at 53 to the lug 43. This pawl 52 is urged in a counterclockwise direction by a spring 54. A fourth pawl 55 is pivotally connected at 56 to the lug 44. The pawl 55 is urged in a counter-clockwise direction by a spring 57.

The springs 47, 51, 54 and 57 are arranged to urge the operating ends of the pawls upwardly. The springs are of proper strength to urge the pawls upwardly when they are not in engagement with an insulating panel B. However, these springs are not of sufficient strength to cause the operating ends of the pawls to dig into the insulation panels when a panel is above the pawl.

The pawl 45 is provided with an operating end 59 designed to engage against the rear edge of a panel B to move the panel in unison with the platform 27. The pawls 49, 52 and 55 are provided with similar operating ends 60, 61 and 62. As the platform 27 reciprocates successive pawls engage the rear edge of the panel to advance the panel to a different position. The purpose of this arrangement will be later described.

The cylinder 33 is of proper length to move the platform 27 a distance slightly greater than the distance between the operating ends of the various pawls. When the panel B is in its first position below the hopper 15, the rear edge of the panel is first engaged by the pawl 45 and advanced a distance slightly greater than the distance between successive pawls. The platform 27 then reciprocates in the opposite direction by springs 29 and 30, the pawls 49, 52 and 55 sliding beneath the panel until the operating end 60 of the pawl 49 clears the rear edge of the panel being advanced. Upon reciprocation of the platform 27 to the left as viewed in Figures 1 and 2, the panel B is then reciprocated by the pawl 49 to a distance of somewhat more than the space between adjacent pawls. Upon return reciprocation of the platform to the right, the pawls 52 and 55 slide beneath the panel B until the operating end 61 of the pawl 52 clears the rear edge of the panel. During the next reciprocation of the platform 27 the panel B is further advanced a distance slightly greater than the distance between the pawls. Upon return reciprocation of the platform toward the right, the pawl 55 slides beneath the panel until the operating end 62 thereof clears the rear edge of the panel. During the next reciprocation of the platform 27 the panel B engaged is moved from beneath the hopper 15.

It will be seen that the rear edge of the lowermost panel B in the hopper 15 is supported by the hook end 22 of the lever 21 while the forward end of this panel rests upon and is supported by the panel being moved. Upon movement of the fed panel from beneath the hopper the forward edge of the lowermost panel in the hopper drops downwardly onto the tracks 11. At ap-

proximately this point of operation the lever 21 is actuated by the hydraulic mechanism 25 to release the rear edge of this lowermost panel. The lever 21 engages the next above panel to support the same after the panel moves to its next position by means of the dog 45.

The tracks 11 guide the panels B beneath the wire rod inserting apparatus indicated in general by the numeral 63. This device takes wire from a suitable source of supply not illustrated in the drawings, but shown as entering from the left of the machine over a guide roller 64. The wire 65 passes beneath a plurality of wire straightening rollers 66 mounted on each side of the device in staggered relation. One wire 65 is supplied to each side of the wire inserting device 63 so that two wire rods may be simultaneously inserted into the panel B.

As indicated in Figures 3, 4, 6, and 9 of the drawings the wires 65 extend between rollers 67 and 69 mounted upon parallel shafts 70 and 71 respectively. The rollers 67 are mounted upon the shaft 70 which also supports a gear 72. The shaft 71 supporting the rollers 69 also supports a gear 73 which is in mesh with the gear 72. As a result the rollers 67 and 69 rotate in opposite rotative directions in unison. The rollers are grooved as indicated at 74 and 75 respectively so that the wire is driven downwardly by these rollers. The shaft 71 is supported by a pair of rubber bushings 68. In normal position, the shafts 70 and 71 support the rollers 67 and 69 spaced apart a distance slightly less than the diameter of the wire being driven. Since the shaft 71 is resiliently supported, the rollers clamp the wire resiliently therebetween. The resilient bushings 68 also compensate for wire irregularities.

As best indicated in Figure 5 of the drawings the shaft 70 is provided with a disc 76 pinned thereto for rotation therewith. A ratchet wheel 77 is rotatably supported upon the shaft 70 adjacent to the disc 76. A pinion 79 is connected to the ratchet wheel 77 to rotate in unison with this ratchet wheel. Ratchets or pawls 80 are pivotally supported at 81 to the disc 76. These ratchets 80 are urged against the ratchet wheel 77 by springs 82 interposed between the ratchets and fixed lugs 83 on the disc 76.

A cylinder 84 is arranged on a vertical axis within the housing 85 forming a part of the wire inserting apparatus 63. A piston 86 is reciprocable vertically within the cylinder 84. A rack 87 is connected to the piston 86 to reciprocate therewith. The rack teeth 89 are in mesh with the pinion 79 so that vertical reciprocation of the rack and piston rotates the pinion 79 and the ratchet wheel 77 connected thereto. A bearing support 90 engages the rear surface of the rack 87 opposite the point of engagement with the pinion 79 so as to reinforce the rack and prevent cocking of the piston 86.

As the rack 87 moves downwardly the pinion 79 and ratchet wheel 77 are rotated in a clockwise direction about the shaft 70. The ratchet wheel 77 engages one of the ratchets 80 so as to cause simultaneous rotation of the disc 76 in a clockwise direction. The ratchets 80 may be spaced so that only one of the ratchets engages the ratchet wheel at any time so as to decrease the lost motion as the ratchet gear is rotated.

Rotation of the disc 76 causes simultaneous rotation of the shaft 70 in a clockwise direction and rotation of the shaft 71 in a counter-clockwise direction. As the wire 65 is gripped between the rollers 67 and 69 supported by these shafts, the

wire is driven downwardly by the rollers during this downward movement of the piston 86.

When the piston 86 moves into its downward extreme position the downward movement of the piston is stopped and the piston is reciprocated upwardly. Upward movement of the rack 87 acts to rotate the pinion 79 and ratchet wheel 77 in a counter-clockwise direction. During this upward reciprocation the disc of the ratchet wheel 10 does not engage the ratchets 80, the operating ends of the ratchets merely riding over the ratchet wheel teeth. Thus during upward reciprocation of the piston 86 the rollers 67 and 69 remain stationary.

15 A wire guide and die is supported on each side of the wire insert apparatus 63 and is indicated in general by the numeral 91. This guide 91 is illustrated in section in Figure 10 of the drawings. The guide 91 includes a lateral projection 92 on the housing 85 having a vertical passage 93 therethrough. A hardened sleeve 94 having a pointed upper end 95 extends through this projection 92. The sleeve 95 is provided with an aperture 96 therethrough for accommodation of the wire 65. 20 A disc 97 is mounted on the lower end of the projection 92. This disc is provided with a central aperture 99 therethrough which is aligned with the aperture 96 of the sleeve 94. Flat head screws 100 or other suitable means support this disc or die 97 in place. The disc is provided with a downward central projection 101 encircling the aperture 99 and extending into close proximity with the cooperable portion of the mechanism.

25 The wire inserting apparatus is formed of two main portions, one of which is fixedly secured relative to the tracks 11 and the other part of which is laterally movable so as to shear off the wire rod when it has been inserted a suitable distance. Figures 7 and 8 of the drawings show the

30 bottom views of this portion of the apparatus when the structure is in both extreme positions. The fixed portion of the apparatus includes a pair of spaced supporting legs 102 and 103 with a connecting frame 104 extending therebetween. This 35 connecting frame includes a pair of vertically extending guide blocks 105 and 106 which are integral with or secured to the connecting frame member 104. These guide blocks 105 and 106 are provided with vertically extending grooves 107 and 109 respectively.

40 The fixed lower section of the wire inserting apparatus which may be indicated in general by the numeral 110 also includes a pair of vertically spaced transversely extending shafts 111 and 112.

45 These shafts 111 and 112 are mounted in upwardly extending side walls 108 on the supporting legs 102 and 103. The position of these shafts is best indicated in Figures 4 and 5 of the drawings. 50 As the shafts are superimposed only one of the shafts is visible in the bottom plan views of Figures 7 and 8.

55 The upper movable portion of the wire inserting apparatus is indicated in general by the numeral 113 and comprises the major portion of the wire inserting apparatus. This movable portion includes the housing 85 which incorporates the cylinder 84 and the box-like enclosure 114 which encloses the gears 72 and 73, the pinion 79 and ratchet wheel 77 as well as the disc 76 and its ratchet 80. The upper portion is formed in two main parts, the uppermost of which includes the cylinder 84 and the box-like enclosure 114. The lower portion of the movable section 113 includes the bottom closure

plate 115 secured to the lower edge of the enclosure 114. A central box is provided extending downwardly from the closure plate 115 as shown in Figure 5 for accommodation of the rack 87 in lowermost position thereof. The closure plate 115 is also provided with a pair of downwardly extending bearings 116 and 117 which encircle the shafts 111 and 112 and slidably support the upper portion of the wire inserting mechanism relative to the lower portion thereof. The bearings 116 and 117 encircle both shafts 111 and 112 so as to hold the two parts of the device from relative rotation.

The closure plate 115 is also provided with a downwardly extending portion 119 which is hollow in form and includes a horizontal cylinder 120. An end closure plate 121 encloses one end of the cylinder 120 and is attached thereto. A piston 122 is mounted in the cylinder 120 and projects somewhat from the open end of the cylinder. A lever 123 is pivoted at 124 to the fixed connecting frame member 104 of the fixed portion of the device. One end 125 of this lever is rounded for engagement with the projecting end of the piston 122. The other end of the lever 123 is pivotally connected at 126 to a link 127, which in turn is connected to the housing 129 pivotally supported by the bottom closure plate 115.

A spring 130 is interposed between an off-set portion 131 of the housing 129 of the link 127 and a suitable shoulder 132 on the fixed frame 104. An additional spring 133 is interposed between the lever 123 and the fixed leg 132. The spring 133 tends to pivot the lever 123 in a clockwise direction as viewed in Figures 7 and 8. The spring 130 acts through the link 127 against the pivot end 126 of the lever 123 to also tend to urge the lever 123 in a clockwise direction.

The bottom closure plate 115 is provided with a pair of spaced downwardly extending projections 134 and 135 which act to support vertically extending guide blocks 136 and 137. These guide blocks 136 and 137 are arranged in surface contact with the previously described guide blocks 135 and 136 and act normally to close the grooves 107 and 109. In other words, when the guide blocks are in the position shown in Figure 7 of the drawings, the grooves 107 and 109 are closed so as to form a tubular conduit through which the wire may extend. The guide blocks described extend from a point closely adjacent to the wire cutting die 97 to a point adjacent to the surface of the panel B which passes beneath the wire inserting device. Therefore the wire is guided through a substantially continuous closed passage which starts just below the wire driving rollers 67 and 69 to the surface of the panel B. As the wire is driven downwardly by the rollers 67 and 69 and is held in vertical position it can not buckle or bend intermediate its ends. As the panels B are usually formed of insulating material which is fibrous in nature and not extremely hard, the wires are driven straight through the insulating material to project a suitable distance therebetween.

This wire driving operation takes place as has been described when the apparatus is in the position illustrated in Figure 7 of the drawings. After the wire has been inserted to the proper depth the wire is cut off by means of the wire die illustrated in Figures 10 and 11 of the drawings. In accomplishing this wire cutting operation the entire movable portion of the wire inserting apparatus moves laterally from the posi-

tion shown in Figure 7 of the drawings to the position shown in Figure 8 thereof.

To accomplish the wire cutting operation the piston 122 is moved in its cylinder 120 in a direction to pivot the lever 123 in a counter-clockwise direction as viewed in Figures 7 and 8. As the piston 122 pivots the lever 123 the lever acts through the pivotal connection 126, the link 127 and the pivotal connection 129 to slide the entire movable portion of the apparatus along the superimposed shafts 111 and 112. This compresses the springs 130 and 133 and acts to move the guide blocks 136 and 137 laterally so as to open the forward ends of the grooves 107 and 109. When the movable portion of the apparatus reaches the position shown in Figure 8 of the drawings, it will be noted that the grooves 107 and 109 are no longer enclosed by the movable blocks 136 and 137 and the wires may be moved in the direction of the arrows in Figure 8 of the drawings in further advancing the panel B. At the same time the wire cutting die 97, forming a part of the movable portion of the apparatus, is moved laterally with respect to the fixed blocks 135 and 136 so that the opening 99 through the die moves out of registry with the grooves 107 and 109. This lateral movement of the wire cutting die shears the wire off along the top of the guide block 136 so that the portion of the wire inserted through the panel is free and separate.

It will be noted that the grooves 107 and 109 are arranged to open forwardly when the movable portion of the device is moved into the position shown in Figure 8 so that upon forward movement of the panel B the wires are free to leave the slots 107 and 109 and to travel forwardly with the panel.

From this explanation the operation of the wire driving apparatus is believed obvious. The wires are first driven downwardly through the panel by the driving rollers 67 and 69 which force the lower ends of the wires through the panel so that they depend a suitable distance beneath the panel. After the wires have been driven to the proper depth they are sheared off at a point spaced above the panel in the manner described. As the wires are sheared off the forward sides of the guide grooves through which the wires extend are opened so that the wires may leave the grooves and move forwardly with the panel. The pressure is then relieved within the cylinder 120 so that the springs 130 and 133 may pivot the lever 123 to its normal inoperative position, thus returning the movable portion of the wire inserting apparatus into readiness for the next wire inserting operation and aligning the grooves 107 and 109 with the respective die openings 99. Simultaneously the forward sides of the grooves 107 and 109 are closed by the movable guide blocks 136 and 137.

The wire crimping apparatus is shown in general in Figure 1 of the drawings and indicated by the numeral 139. The structure of this device is believed best illustrated in Figures 13 through 19 of the drawings. The device acts to engage the wire both above and below the panel B and to bend the wire so that it will become firmly anchored and embedded in the concrete building block as the block is molded.

The crimping device includes a hollow body 140 having detachable ends 141 and 142 thereupon. The ends 141 and 142 are hollow in form and are attached to the body of the device by

means of bolts or cap screws 143 and 144 respectively.

The body 140 is provided with a longitudinally extending slot 145 extending therethrough through which the panel B may extend. The angular tracks 11 are also shown extending through the body, these tracks serving to support the crimping device. The body 140 is also provided with two relatively wide vertically extending slots 146 and 147 through which the inserted wires may extend. The slots 146 and 147 are the full height of the inserted wires so that the wires may pass through the block without interference. A pair of stationary forming dies 149 and 150 are secured to the block body 140 inwardly of the slots 146 and 147 above the level of panel B. The dies 149 and 150 are anchored to the inner opposed walls of these slots 146 and 147 by cap screws 151 or other suitable means. A similar pair of fixed forming dies 152 and 153 are secured to the inner opposed walls of the slots 146 and 147 below the level of the panel B. These lower forming dies are held in place by cap screws 154 or other suitable means. The formation of these dies is best illustrated in Figure 18 of the drawings. It will be noted that the body of the die is provided with two spaced grooves 155 and 156 separated by an outwardly projecting rounded rib 151. Rounded ribs 159 and 160 are provided along the upper and lower edges of the die. The entrance end of each of the dies is tapered as indicated at 161 so as to guide the wires into place.

A pair of cooperable movable dies 162 and 163 are supported for movement toward and away from the fixed dies 149 and 150. The movable die 162 is mounted upon a rectangular plunger 164 which is reciprocable in a cylinder 165 between the slot 146 and one end of the body 140. The die 163 is mounted upon a rectangular plunger 166 which is slidable in a cylinder 167 between the slot or groove 147 and the opposite end of the body 140.

A movable die 169 is designed to cooperate with a fixed die 152 and to move toward or away therefrom. The movable die 169 is mounted upon a rectangular plunger 170 which is reciprocable in a cylinder 171 extending between the slot 146 and the adjacent end of the body 140. A fourth movable die 172 is mounted for movement toward or away from the fixed die 153 and is mounted upon the rectangular plunger 173 slidable in a cylinder 174 extending between the slot 147 and the adjacent end of the body. The plungers 164 and 166 are preferably aligned and the plungers 170 and 173 are also preferably aligned.

As shown in Figures 15 to 17 of the drawings the movable dies are provided with a pair of rounded projecting ribs 175 and 176 having a groove or channel 177 therebetween. The leading edge of each die is tapered as indicated at 179 so as to guide the wires between the dies. The fixed dies 149, 150, 152 and 153 are provided with extensions 158 having continuations of the rib 159 thereupon. These continuations 158 diverge outwardly slightly and tend to bend the crimped wires slightly on either side of the boards as the boards advance. A cross head 180 is provided with apertures 181 and 182 for accommodation of the projecting ends of the plungers 164 and 170. Pins 183 and 184 extend through the plungers and outwardly of the cross head 180. Springs 185 are interposed between the body and the cross head 180. As a result the springs 185 tend to normally retract the plungers 164 and 170 and to urge the movable dies 162 and 169 away from the cooper-

able fixed dies 149 and 152. A similar cross head 186 is provided with apertures 187 and 189 for accommodation of the projecting ends of the plungers 166 and 173. Pins 190 and 191 extend through the plungers 166 and 173 outwardly of the cross head. Springs 192 are interposed between the cross head and the body 140. These springs normally tend to retract the plungers 166 and 173 and to urge the movable dies 163 and 172 away from the corresponding fixed dies 150 and 153.

It will be noted that upon the application of hydraulic pressure into the hollow ends 141 and 142 of the crimping apparatus the plungers 164 and 166, 170 and 173 are urged inwardly, the respective movable dies bracing the wires against the corresponding fixed dies and crimping the ends of the wire. As a result the wires are given two or more reverse bends both above and below the panel B so that the wires can not be pulled from the panel without destroying the panel and so that opposite ends of the wires may be embedded in the concrete on opposite sides of the insulating panel so as to reinforce the block and to prevent the block from splitting through the insulation panel.

After the wires have been crimped, the hydraulic pressure is released and the springs 185 and 192 act to return the movable dies into their outer extreme position. As the fixed dies extend longitudinally of the apparatus and parallel to the direction of motion of the panels, the panel B may be advanced after the wires are crimped to place a new pair of wires between the crimping dies.

In the construction described the panels B are advanced forwardly into four different positions by the panel feeding element 26, hereinbefore described, and at each of the positions, a pair of wires are inserted through the panel so as to extend above and below the same. Thus as shown in Figure 12 of the drawings, there are four pairs of reinforcing wires extending through the panel. As the panel is advanced each successive pair of wires is urged between the crimping dies which act to bend the projecting end of the wire into the form illustrated in Figure 12 of the drawings. Obviously the apparatus may be arranged to insert a greater or lesser number of wires than that illustrated.

The hydraulic control system, by means of which the various portions of the apparatus is controlled, is best illustrated in Figure 20 of the drawings. This view shows the various portions of the device diagrammatically. In this figure I disclose a motor or other source of power supply 193 which acts to operate the hydraulic pump 194. The pump 194 is provided with an inlet 195 which extends into a hydraulic liquid tank 196 and receives hydraulic fluid therefrom. The pressure outlet of the pump 194 is indicated at 197 and extends to a reversing valve 199 which is shown as submerged in the tank 196. The valve 199 includes two cylinders 200 and 201. The cylinder 200 is provided with a three lobe piston valve 202 which is operable between two extreme positions. A piston rod 203 is connected to the valve 202 and is equipped with an operating yoke 204. The yoke 204 is movable between two extreme positions by an operating pin 205 on one arm of a bell crank lever 206. One arm 207 of the bell crank lever 206 is connected by a resilient spring or link 209 to the plunger 210 of a solenoid 211. The bell crank lever is pivotally supported to a fixed casing at 212. The other

arm 213 of the bell crank lever 206 is pivotally connected at 214 to a push rod 215 which is slidably supported in a pivotal bracket 216. A spring 217 is interposed between the bracket 216 and the pivotal connection 214, while a second relatively weak cushioning spring 219 is provided between the bracket 216 and the extremity of the push rod 215. The push rod and its spring 217 is arranged to hold the bell crank lever 206 in either extreme position.

In one position of the piston valve 202 the pressure inlet port 220 is connected to a connecting port 221 leading to the cylinder 201. The cylinder 201 is equipped with a loosely fit piston 222 connected by a piston rod 223 to the pivotal connection 214 between the bell crank lever 206 and the push rod 217. The cylinder 201 is provided with an outlet conduit 224 leading to a valve 225. The valve 225 is provided with a cylinder 226 having a three lobed piston 227 therein. This piston 227 is normally biased to the right as indicated in Figure 20 by a spring 229.

The inlet pressure port 230 of the valve 225 is normally connected to an outlet conduit 231 leading to the extremity of the cylinder 120 of the wire driving unit 63. The inlet end of the cylinder 120 is also connected to an outlet port 232 communicating with the conduit 233. The conduit 233 is connected through a check valve 234 to a conduit 235 leading to the inlet port 236 of the cylinder 33. The check valve 234 is also connected by conduits 237 and 239 to a point between the center lobe and right hand lobe of the valve piston 221. The check valve 234 is likewise connected by conduits 237 and 240 to a point between the center lobe and right hand lobe of the valve plunger 202.

The cylinder 33 is provided with an outlet port 241 intermediate its ends connected by a conduit 242 to an inlet port 243 of the valve 225. When pressure is exerted through the conduit 242 the piston valve 227 is moved to the left compressing the spring 229 and forming a pressure connection between the center lobe and the right hand piston lobe to the conduit 239. Simultaneously the conduit 231 is connected to an exhaust port 244. A second outlet port 245 is provided near the right hand end of the cylinder 33 which is connected by a conduit 246 and 247 to the upper extremity of the cylinder 84. An outlet port 249 is provided near the lower end of the cylinder 84, which is uncovered when the piston 86 has travelled into extreme position. The outlet port 249 is connected by a pressure conduit 250 to passages 251 and 252 in the crimper body 140. These passages 251 and 252 lead to the hollow heads 141 and 142 and are designed to urge the plungers 164, 170, 166 and 173, carrying the movable wire crimping dies inwardly to crimp wire therebetween.

The outlet port 245 of the cylinder 33 is also connected by conduits 246 and 253 to a valve 254. This valve 254 is mounted above the path of movement of the panels B and includes a two lobed piston 255 projecting through the lower end of the valve casing and provided with a roller 256 engageable with the panels B. When there is no panel beneath the piston 255 the piston valve 255 is urged into lowered position by a biasing spring 256. When a panel B is positioned beneath the plunger 255 this plunger is held in elevated position.

A pressure inlet port 257 is provided in the valve which is normally closed by the lower lobe of the plunger piston 255. However, in lowered

position of this valve the inlet port 257 is connected to the outlet port 259 connected to a conduit 260.

The conduit 260 extends to the lower end of a hydraulic cylinder 261 having a piston 262 therein. This piston 262 is engageable against the arm 24 of the bell crank lever 21 and a hook end 22 which engages beneath the lowermost panel in the hopper 15.

10 A normally open micro switch 263 is mounted on the frame of the apparatus in the path of movement of the cylinder 33. When the cylinder 33 moves to its extreme right hand position, as viewed in the drawings, the micro switch is closed so as to close a circuit. A second micro switch 264 is arranged in the path of movement of the panels upon the track 11. When the track is filled with panels B, the normally closed micro switch 264 is arranged to open and break the circuit.

20 The circuit described is designed to energize the solenoid 211. The normally open switch 263 and normally closed switch 264 are arranged in series between the source of current and the solenoid 211. When the cylinder 33 is fully retracted the switch 263 is closed to close a circuit to the solenoid 211. This circuit will be closed each time the cylinder 33 reciprocates until the panels fill the available space on the track 11. At this time the micro-switch 264 will open the circuit and the circuit will remain open until some of the boards are removed from the track whereupon the operation will continue.

30 The operation of the device is normally controlled by the presence or absence of insulation 35 panels on the outlet guide rails, as will be later described. During the normal cycle of operation, the previously driven wires are first sheared off. Next the board is advanced by movement of cylinder 33. During this movement the shearing 40 means is returned to starting position. When the advancement of the board is complete, the wire driving apparatus forces new wires through the board. After insertion the wires are crimped. The wire driving mechanism and the crimping 45 device are next returned to starting position. The cylinder 33 also returns to starting position for a new cycle. Whenever no board is positioned below the valve 254, the board release mechanism operates to release another board 50 from the hopper.

55 The operation of the various units of my apparatus have been described in conjunction with the devices themselves. The apparatus is automatic as long as the panels B and the wire for insertion therethrough are supplied. When the cylinder 33 is moved to its extreme right hand position the microswitch 263 is closed, closing the described circuit to the solenoid 211. The solenoid core 210 is drawn upwardly pivoting the bell crank lever 206 in a clockwise position into the position illustrated in Figure 20 of the drawings. Fluid under pressure from the pump 194 then passes through the conduit 197 into the valve cylinder 200 in the space between the left hand lobe and the center lobe of the valve plunger. With the plunger in the position shown the fluid under pressure extends through the port 221 into the cylinder 201 and through the conduit 224 to the center portion of the valve 225. 60 As the valve plunger 227 is normally biased to the right the fluid passes through the conduit 231 into the end of the cylinder 120. The piston 122 is moved in the cylinder 120 pivoting the lever 123 in a manner to shear off the wire which has been previously inserted and to move the guide

blocks 136 and 137 from the position illustrated in Figure 7 to the position shown in Figure 8 of the drawings, thus allowing the inserted wires to be moved out of the grooves 107 and 109. As the piston 122 reaches its extreme position, fluid is transmitted through the conduit 233 past the check valve 234 and through the conduit 235 to the left hand end of the cylinder 33. This fluid acts against the relatively fixed piston 36 to move the cylinder 33 to the left, thereby acting to advance a panel B along the track 11 in the manner previously described.

As the cylinder 33 moves to the left the outlet port 241 is uncovered by the piston 36 and the fluid under pressure passes through the fluid line 242 to the right hand end of the valve plunger 227. This fluid acts to compress the spring 229 and move the plunger 227 to the left. This action cuts off the pressure to the conduit 231 and the conduit 231 is connected to the exhaust pressure line 244 through the valve 225, thereby releasing the pressure upon the piston 122 and allowing the springs 131 and 133 to return the piston 122 to its normal position. Simultaneously fluid under pressure is transmitted between the center lobe of the valve piston 227 and the right hand lobe thereof to the conduit 239 which transmits pressure to conduits 237 and 235 to the left hand end of the cylinder 33 to continue the movement of the cylinder relative to the piston 36. The check valve 234 closes to prevent the return of pressure into the cylinder 120.

When the cylinder 33 reaches its extreme left hand position the outlet port 245 is opened and fluid under pressure is transmitted through conduits 246 and 247 to the top of the cylinder 84. This action urges the piston 86 downwardly, thus acting to drive a new pair of wires through the panel B located therebeneath. When the piston 86 reaches its lowest position, fluid is also transmitted through the connection 250 to the ends of the crimping apparatus, thus urging the movable dies against the wire and crimping the wires above and below the panel.

At the same time pressure is supplied to the cylinder 84 pressure is also supplied through the conduit 253 to the valve 254. If there is no panel B beneath the roller 259, the plunger 255 has dropped and pressure will be exerted through the connection 260 to the lower end of the cylinder 261. This pressure urges the piston 252 upwardly, pivoting the bell crank lever 21 and releasing the next lowest panel B from the hopper 15. If there is a panel beneath the roller 256 the valve 254 remains closed.

When the cylinder 33 reaches its extreme right hand position there is no further outlet for the hydraulic fluid in the system. Accordingly pressure builds up within cylinder 33, fluid lines 235 and 237, the center part of cylinder 225, fluid line 224, and the cylinder 201 until sufficient pressure is provided to urge the piston 223 to the left against the spring pressure. In doing so, fluid under pressure flows past the loosely fit piston 222, and exerts its force against the larger area of the piston end. This action actuates the bell crank lever 206 into its opposite extreme position, changing the position of the reversing valve plunger 202.

When the position of the valve 202 is reversed the valve plunger 202 moves to the left uncovering a second outlet port 265 connected to a pressure conduit 266. This conduit is connected by a by-pass connection 267 to a low pressure valve 269 which is connected to the tank 196. As a

result the pressure which is exerted in the conduit 266 is substantially less than the pressure which is exerted through the previously described pressure conduits. The conduit 266 is connected to the closed interior of the casing 114 containing the rack 87 for the various gears described. The pressure conduit 266 urges the piston 86 to its upper extreme position. The pressure within the conduit 266 is also exerted through the conduit 250 to both ends of the crimping device 139. However, the reduced pressure is insufficient to hold the plungers 164, 166, 170 and 173 inwardly and the springs are of sufficient strength to return these plungers to their outer positions so that the crimping dies will move to inoperative position.

During this position of the valves, the left hand end of the cylinder 33 is connected to exhaust pressure. This connection extends through the conduits 235, 237, 240, the cylinder 200 connecting the port 221, cylinder 201, and connecting the port 270 leading through the wall of the cylinder 201 to the right hand side of the valve plunger 202 which is open to the liquid tank when this plunger 202 is moved to the left from the position shown in Figures 20 and 24. As a result the cylinder 33 is returned to its extreme left hand position by means of the springs 29 and 30. As the cylinder 33 reaches its extreme right hand position, the micro-switch 263 is again actuated closing the circuit to the solenoid 211 and pivoting the bell crank lever 206 in a clockwise direction. This again starts a cycle of operation which continues until the space on the panel track 11 is filled with unused panels. A pressure relief valve 271 is provided as a by-pass from the pump outlet 197. This relief valve normally does not function unless some part of the system does not operate properly.

Each of the various devices are connected by exhaust pressure return lines to prevent the building up of pressure on the wrong side of the pistons. It will be noted that one such return line 272 extends through the crimping head 140 near the ends of the plungers 164 and 170 to return any liquid reaching this point to the tank 196. A similar return line 273 is connected to encircle the plungers 166 and 173. The return lines 272 and 273 join to form a return conduit 274 which leads into the tank 196.

Return lines 275 and 276 also encircle the piston plunger 255 and join to form a conduit 277 connected to the return line 274. The conduit 276 is connected with a groove encircling the plunger 255 below the pressure inlet port 257 while the connection 275 is normally connected through the piston with the conduit 260 leading to the cylinder 261 so that this cylinder 261 may be evacuated when pressure is not being applied thereto. A conduit 279 also encircles the piston 262 to prevent leakage of fluid thereabout.

Another exhaust pressure connection extends from the right hand end of the cylinder 33 to the return pressure line, this conduit being indicated by the numeral 280.

It will be seen that my device functions to remove superimposed panels from a hopper, to advance the panels along a track in spaced steps, to drive a pair of wires through the panel at spaced intervals between the steps of movement, to shear off the inserted wire, and to crimp the wires on both sides of the panel. My device reverses automatically at the end of each cycle of operation and continues until the current to the supply motor 193 is cut off or until the track

11 has been filled with a proper supply of formed panels. As soon as some of the panels are removed from the track 11, the system again starts into operation.

In accordance with the patent statutes, I have described the principles of construction and operation of my apparatus for forming building block insulating members, and while I have endeavored to set forth the best embodiments thereof, I desire to have it understood that these are only illustrative thereof, and that obvious changes may be made within the scope of the following claims without departing from the spirit of my invention.

I claim:

1. A wire driving apparatus for driving wire through a panel, the apparatus including a panel support, a wire guide mounted adjacent said support, said guide member having an open sided groove therein, a relatively movably mounted means for closing the open side of said groove in one position thereof, wire driving means for moving a wire longitudinally through the groove while the open side thereof is closed, and means for moving said open side closing means to open said groove.

2. The structure described in claim 1 and including a wire shearing means supported adjacent to said wire driving means.

3. The construction described in claim 1 and including a tubular member mounted adjacent to said wire driving means through which the wire extends between said wire driving means and said open sided groove.

4. A wire driving device for driving a wire through a panel, the device including a panel support, a movably mounted guide mounted adjacent said panel support, said guide having a groove therein extending toward said panel support, a means for closing the open side of said groove in one position of said guide, said guide being laterally movable relative to said groove closing means to selectively close the groove or expose the same, a second wire guide supported adjacent to said first named guide and registerable with said groove in closed position thereof, and means for driving the wire through said guides.

5. The structure described in claim 4 and including a shearing die mounted between said groove and said second guide.

6. A panel advancing device for advancing a panel along a track, the device including a panel hopper, a reciprocable means positioned beneath said hopper, a track beneath said hopper on which the lowermost panel of the hopper is supported, a series of panel engaging means on said reciprocable means, said panel engaging means successively engaging an edge of the panel upon continued reciprocation of said reciprocating means to advance the panel in steps from beneath said hopper.

7. The structure described in claim 6 in which the means engageable with the panel edge are spring urged against the panel.

8. A panel advancing means for advancing panels along a track, the means including a hopper mounted above the track for supporting a series of superimposed panels, the lowermost panel in the hopper resting upon the track, a reciprocating device supported beneath said track, means for reciprocating said device longitudinally of said track, and a series of longitudinally spaced dogs on said device successively engageable with the rear most edge of the panel supported upon

the track, reciprocation of said device successively engaging said dogs with the rear most edge of the panel to advance the panel in steps from beneath said hopper.

5 9. A construction described in claim 8 and including releasable means for supporting the rear edge of the panel next above the lowermost panel.

10 10. A wire crimping device including a pair of parallel fixed dies, a track slidably supporting a panel for movement past said dies, a wire inserted through the panel, and movable past said dies, and cooperable dies movable toward said fixed dies for crimping the wire on opposite sides of said panel.

15 11. The structure described in claim 10 and including hydraulic means for moving said movable dies.

20 12. The structure described in claim 10 and including hydraulic means for moving said movable dies in one direction and resilient means for urging said movable die in the opposite direction.

25 13. A wire crimping device for crimping wires inserted through a panel, the device including a track along which said panel is movable, a fixed die extending along the path of movement of the wires on both sides of the panel, and movably supported dies cooperable with said fixed dies to crimp the wire on both sides of the panel, and means for moving said movable dies.

30 14. A device for crimping pairs of wires inserted through a panel including a means for supporting the panel for movement, a fixed die extending along the path of movement of each of the wires on one side thereof, and movable dies extending along the path of movement of the wire on the opposite side thereof, and means for moving the movable dies against the wire to force the same against the fixed dies.

35 15. A hydraulically operable apparatus for inserting wires through panels, the apparatus including a reciprocable cylinder, hydraulically operable means for reciprocating the cylinder, means connected to the cylinder for advancing a panel as the cylinder reciprocates, a wire driving apparatus, hydraulic means for operating said wire driving apparatus, a wire crimping apparatus, hydraulic means for operating said crimping apparatus, a wire shearing device, and hydraulic valve means for actuating said cylindrical wire driving apparatus, crimping apparatus and shearing device in predetermined sequence.

40 16. An apparatus for inserting reinforcing wires through a panel, the apparatus including a panel support, reciprocating means for moving the panel along said support, said panel moving during movement of the reciprocating means in one direction and remaining stationary during movement of the reciprocating means in the opposite direction, and means for inserting a wire rod through the panel, the wire driving means including means enclosing the wire during the wire driving operation and opens during advancement of the panel.

45 17. A wire driving apparatus including a pair of rollers between which the wire extends, means rotatably supporting said rollers in position to engage opposite sides of the wire, means for rotating said rollers for driving said wire, means supported adjacent to said rollers including an open sided groove through which said wire extends during movement thereof, means relatively movably supported adjacent to said last named means for closing the open side of said groove during longitudinal driving movement of the

wire, and means for moving said groove closing means into and out of groove closing position.

18. A wire driving apparatus for driving a wire through a panel, the apparatus including a pair of wire driving rollers between which the wire extends, means rotatably supporting said rollers in position to engage opposite sides of the wire, a guide member mounted adjacent to said rollers, said guide member having an open sided groove therein, relatively movably mounted means for closing the open side of said groove during driving movement of the wire by said guide rollers, and means for moving said groove closing means after the wire driving operation.

19. A wire driving apparatus for driving a wire rod through a panel, the drive means including a pair of drive rollers, a guide through which the wire is driven, a panel support, a second guide between the first guide and a panel on said support movable into or out of alignment with said first guide, movement of said second guide relative to said first guide shearing the wire therebetween, the second guide including an open sided groove in said second guide, and means closing the open side of said groove when said groove is aligned with the first guide and opening the groove when the second guide is moved out of alignment with the first guide.

20. An apparatus for inserting reinforcing wires through a panel, the apparatus including means for moving the panel at spaced intervals with reference to a fixed point, and means for inserting a wire rod through the panel during periods when said panel is not moving, said inserting means including means having an open side for partially embracing the wire, and relatively movable means for closing said open side of said embracing means during the wire driving operation and moving out of closing position during movement of the panel.

21. An apparatus for inserting reinforcing wires through a panel, the apparatus including a panel support, means for moving the panel along said support at spaced intervals, and means for inserting a wire rod through the panel during periods when said panel is stationary, said inserting means including guide means for the wire provided with an opening adjacent one side and means for at least partially closing said opening during the wire driving operation, said closing means being open during the advancement of the panel.

22. An apparatus for inserting reinforcing wire through a panel, the apparatus including a panel support, reciprocating means for moving the panel along said support, said panel moving during movement of the reciprocating means in one direction and remaining stationary during movement of the reciprocating means in the opposite

direction, and means for inserting a wire rod through the panel, said inserting means including means for embracing a segment of the wire and means confronting said embracing means only during the wire driving operation.

23. A wire driving apparatus for driving a wire rod through a panel, the drive means including a pair of drive rollers, a guide through which the wire is driven, a panel support, a second guide between the first guide and the support movable into or out of alignment with said first guide, movement of said second guide relative to said first guide shearing the wire therebetween, said second guide being spaced from the panel support for the accommodation of a panel and also being provided with a side opening, and means for at least partially obstructing said side opening when said second guide is aligned with the first guide and freeing said opening sufficiently for separation of the wire from said second guide when the second guide is moved out of alignment with the first guide.

24. A device for inserting a wire through a panel including a panel supporting means, panel advancing means for advancing a panel on said supporting means, wire driving means mounted adjacent to the path of movement of the panel, means for guiding a wire through said panel to extend therethrough at substantially right angles thereto, means for shearing off the wire at a point spaced from the panel, said panel advancing means moving the panel with the wire projecting right angularly therefrom, and means for crimping the wire at points spaced from the panel.

25. The structure described in claim 24 and in which the crimping means engages the wire at points spaced from the panel.

26. The structure described in claim 24 and in which the crimping means engages the wire at points spaced from the panel and bends the wire angularly while still extending substantially normal to the panel.

JOHN T. GONDEK.
